LADLE MAINTENANCE APPARATUS

June H. Reighart, Cleveland, Ohio

Application August 10, 1953, Serial No. 373,118

3 Claims. (Cl. 22—85)

This invention relates to apparatus useful in the maintenance of ladles of the type used for molten metals.

It is common practice in steel mills, to receive from a furnace and convey molten metal in a ladle of the type having a bottom nozzle. The nozzle which is of refractory material is used as a valve, being closed by inserting there in the end of a stopper rod, which rod extends up to the top of the ladle and is raised out of engagement with the nozzle when it is desired to have the nozzle open as for discharge of metal into a mold.

There has been a problem in that the nozzles burn out and must be replaced after each heat is poured and, because the ladle is extremely hot from the previous heat of metal, considerable time is required in order to allow the ladle to cool to an extent sufficient to allow a man to enter into the ladle and replace the nozzle. In general, the nozzles are tapered inwardly towards their bottoms and are cemented in the ladle, and for this reason cannot satisfactorily be replaced from outside the ladle.

In ordinary practice the ladle has to have a new bottom nozzle in its lining after each heat is poured and the ladle cannot be put back into service until the new nozzle is cemented and dried in place. It requires two and a half to three hours after a heat is poured for an ordinary steel milltype ladle to cool enough to allow a man to enter the ladle. He works under conditions which are even then extremely disagreeable and when his job is complete it still takes another hour to one and a half hours to dry the cement around the new nozzle.

It is an object of the present invention to provide simple and efficient means for overcoming the above-mentioned difficulties.

A further object of the invention is to provide a novel article of manufacture comprising a ladle insert or liner useful in connection with maintenance of a molten metal ladle having a bottom pouring nozzle which must be replaced from inside the ladle and preferably when the ladle is quite hot.

A still further object is to provide a ladle insert or liner comprising a hollow metal shell having heat insulation material therein, and a bottom opening through which a workman may have access to the nozzle of a ladle into which the liner is inserted.

Another object is to provide such an insert or liner with means for placing it in a ladle and removing it therefrom.

A further object is to provide an insert or liner of the character referred to having a door in one side near the bottom thereof for placing tools and material therein.

A still further object is to provide such an insert or liner having a ladder therein by means of which a workman may quickly enter and leave the liner after it is positioned within a ladle.

Another object is to provide an overhanging safety rim ring at the top of the ladle insert adapted to overhang the top of the ladle, when the insert is located therein, and spaced above the ladle rim sufficiently to allow for the escape of heat rising from the ladle.

2

It is also an object of the invention to provide spacer guides around the exterior of the ladle insert to insure center placement of the insert in the ladle so as to provide for air circulation and heat escape between the insert and the ladle.

5 A further object is to provide trunnions on the insert for engagement by the crane trunnion hooks for ease in positioning of the insert within a ladle.

These and other objects and advantages apparent to 10 those skilled in the art from the following description and claims, may be obtained, the stated results achieved, and the described difficulties overcome by the products, articles of manufacture, constructions, combinations, subcombinations, parts and elements which comprise the present invention, the nature of which is set forth in the following general statement and a preferred embodiment of which, illustrative of the best mode in which applicant has contemplated applying the principles, is set forth in the following description and shown in the drawings, and particularly and distinctly pointed out and set forth in the appended claims forming part hereof.

The nature of the discoveries and improvements of the 15 present invention may be stated in general terms as preferably including the method of servicing a molten metal ladle having a bottom pouring nozzle which must be replaced, by placing a heat resisting insert or liner within the ladle so that an operator may enter the heat resisting liner and replace the nozzle without waiting for the ladle to cool. In accordance with the invention, means are provided for lifting the insert or liner into the ladle, preferably 20 with a clearance between the outer diameter of the insert or liner and inner diameter of the ladle, and means are also provided for gaining entry into the insert or liner and operating therethrough upon said nozzle so that the remains of the old nozzle may be chipped out and replaced without waiting for the ladle to cool and without waiting an appreciable time for the ladle to be reheated in order 25 for the nozzle to dry.

By way of example, preferred embodiments of my improved method of servicing a molten metal ladle, and of an improved article of manufacture useful in connection therewith, are illustrated in the accompanying drawings, in which:

Fig. 1 is a top plan view of a conventional molten metal ladle provided with a heat resisting insert or liner constructed in accordance with the invention;

Fig. 2 is a vertical view of the ladle and liner of Fig. 1 partly cut away in order to disclose the interior construction;

Fig. 3 is a cross sectional view along the line 3—3 of Fig. 2;

Fig. 4 is a vertical view showing the liner removed from the ladle, as by a crane hoist;

Fig. 5 is a sectional view along the line 5—5 of Fig. 1 and showing a portion of the top of the ladle and liner and showing a top platform as hereinafter explained.

Referring to the drawings in which similar parts are designated by similar numerals throughout the several views, I have shown a ladle for molten metal such as steel and having an outer metallic shell 10 which may be of steel and an inner refractory lining 11 which may be made up of refractory bricks or which may be unitary and of a material such as silicon carbide.

The ladle is provided with the usual appendages including a pair of trunnion lifts 12, a top spout 13, a lifting bracket 14, for tipping the ladle so that the various oxides and lime making up the top slag will be discharged through the top spout 13, and a bottom casting nozzle 15 which, in accordance with conventional practice is of refractory material and tapered to be of smallest dimension at its bottom and flares outward at its top adjacent the refractory lining material 11. This bottom pouring

nozzle provides for the discharge of clean metal from the bottom of the ladle but it wears very rapidly with use and in usual practice the ladle must be cooled after pouring of each heat in order to put in a new nozzle.

In accordance with the invention, I provide a heat resisting insert or liner comprising, in the illustrated embodiment, steel bucket shaped outer and inner shells, 20 and 21 respectively, with intervening insulating material 22 which may be fibre glass, rock wool, or any other good heat insulating material. This ladle insert or liner is arranged to be inserted within the ladle with a clearance 24 between the outer diameter of the insert and the inner diameter of the ladle refractory material 11.

For the purpose of insuring positive center placement of the insert within the ladle so as to provide positive air circulation and heat escape between the insert and the ladle, spacer guides 20' are equally spaced around the lower circumference of the outer shell 20 of the ladle insert.

The inner and outer walls and the intervening insulation of the insert are all cut out to provide an opening 25 which is somewhat larger than the nozzle 15 to be replaced, and which opening is adapted to be aligned with the area adjacent the nozzle when the insert is placed within the ladle as by a crane hook, the insert being provided with lifting means such as a bale member 27.

Trunnions 26 may be formed upon the bale member 27 for engagement by conventional crane trunnion hooks 26' for ease in the accurate rotary positioning of the insert as the craneman places it in the ladle.

Hand rails 29', of inverted U-shape as shown in the drawings, may be provided at the top of the ladder 28, and extend across the adjacent portion of the rim 29, which forms an approach platform for the ladder.

Entry means are provided so that an operator may enter into the insert, and in the illustrated embodiment such means includes a ladder 28 reaching from the top to the bottom of the insert and cooperating with a rim ring 29 which is secured to the top of the insert and adapted to overhang beyond the outer diameter of the steel shell 10 of the ladle, being spaced above the top of the ladle sufficiently to allow for the escape of heat rising from the ladle.

Additional entry means are also shown comprising a door 30 swingable upon hinges 31 and providing additional access to the interior of the liner so that it may be entered from floor level, as when it is removed from the ladle. If desired, in operation door 30 may be swung open and tools and materials placed within the insert before the insert is lifted up and placed in the hot empty ladle.

Then the operator climbs up to platform 29 and descends down ladder 28 into the interior of the insert where he will find his tools and material and can immediately commence work chipping away the old nozzle 15 and cementing in a new nozzle, and then the job is complete, particularly since it was possible for the ladle nozzle to be replaced under conditions of high ladle temperature so that the new nozzle cement will dry almost immediately.

With the arrangement described the insert may have quite thin metallic walls since the walls and intervening insulation all support each other. It has been found that using the device and method of the invention results in a saving of two to three hours every time that a heat is poured. There is thus provided a device and method of the character described capable of meeting the objects above set forth.

While I have illustrated and described particular embodiments of the invention, further modification and improvements will occur to those skilled in the art. I desire it to be understood, therefore, that the invention is not to be limited to the embodiments shown and I intend in the appended claims to cover all modifications which do

not depart from the true spirit and scope of the invention, and the elements of such claims are intended to include reasonable equivalents.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

Having now described the invention or discovery, the construction, the operation, and use of preferred embodiments thereof, and the advantageous new and useful results obtained thereby; the new and useful constructions, and reasonable mechanical equivalents thereof obvious to those skilled in the art, are set forth in the appended claims.

I claim:

1. A ladle insert for protecting a human operator from the heat of a ladle used for molten metal, and comprising the combination of bucket shaped inner and outer walls 25 and heat insulating material between said walls around the sides of said insert and at the bottom thereof, a ladder extending down into the interior of said insert, a top platform extending from said ladder to a position adapted to overhang a side of the ladle, spacer guide ribs on the exterior of the shell for centering the shell within a ladle, and a door in said ladle insert for providing access thereto.

2. A ladle insert for protecting a human operator from the heat of a molten metal ladle having a bottom nozzle, said ladle insert comprising inner and outer bucket shaped shells and intervening insulation, and having an outer diameter small enough to form a clearance with the inner diameter of said ladle, means for lifting said insert and placing it within said ladle, a top platform extending from the top of the interior of said insert and adapted to overhang a top portion of said ladle, a ladder extending from said platform down to the bottom of said insert, and a tool door providing access to the interior of said insert, with the shells and the insulation at the bottom of said insert being cut away to provide an opening adapted to be aligned with said nozzle for chipping away a burnt nozzle and replacing the same with a new nozzle, and spacer guide ribs on the exterior of the shell for centering the shell within a ladle, whereby in a minimum of time the insert can be furnished with tools and materials and a man can immediately after pouring a previous heat enter into the ladle by way of the insert and replace a burnt out nozzle in a minimum of time and whereby the replaced nozzle will dry in a minimum of time because of the surrounding heat of the ladle.

3. As an article of manufacture as a heat transfer resisting insert for a ladle for molten metal, the combination of a hollow steel shell in the form of inner and outer bucket-shape walls with intervening insulation material located therebetween around the sides and in the bottom of the shell, opening means in the bottom and side of the shell and insulation providing a working space from which a portion of the ladle may be reached from the interior of the shell, means for lifting said shell to place it within a ladle, spacer guide ribs upon the exterior of the shell for centering the shell within a ladle, and an annular rim at the top of the shell adapted to be spaced above and overhang the top of the ladle.
